Patented May 3, 1927.

UNITED STATES PATENT OFFICE.

JOSEPH HAROLD SULLIVAN, OF PORTAGE, WISCONSIN.

INCANDESCENT ELECTRIC-LAMP CONNECTION.

Application filed April 21, 1926. Serial No. 103,593.

My present invention has to do with the mounting or connection of incandescent electric lamps and more particularly to the mounting or connection of such lamps in reflectors used in automobile headlights, and it contemplates the provision of a connection which is simple, compact and reliable and durable in service and is possessed of the other practical advantages hereinafter ascribed to it.

To the attainment of the foregoing, the invention consists in the improvement as hereinafter described and definitely claimed.

In the accompanying drawings, forming part of this specification:

Figure 1 is a view, partly in section and partly in elevation, illustrative of the best practical embodiment of my invention that I have as yet devised.

Figure 2 is a detail elevation taken from the viewpoint indicated by the line 2—2 of Figure 1.

Figure 3 is a fragmentary cross-section taken in the plane indicated by the line 3—3 of Figure 1.

Similar numerals of reference designate corresponding parts in all of the views of the drawings.

I show in Figures 1 and 3 a reflector 1, characterized by a central aperture 2 and having at its inner side an annulus 3 about said aperture and also having at its outer side a boss 4 which surrounds the aperture, the annulus being equipped with diametrically opposite slots 5, Figures 1 and 3. I also show in Figure 1 an incandescent electric lamp 6 which may be and preferably is of conventional type, and is provided with the usual filament 7. The lamp bulb 6 is joined in any appropriate manner to a stem 8 which is dielectric in character and which, for the sake of strength and durability is formed of fiber or equivalent material; the filament 7 having its end portions embedded in and carried through the stem 8 to diametrically opposite longitudinal grooves 9 which extend to the rear end of the stem, Figure 1. The said grooves 9 are for the reception of electric wires 10 designed to be arranged in circuit with a suitable source of electric energy, and it will be noted from Figure 1 that the wires 10 are clamped in position by screws 11 which contact and make electric connection between the filament 7 and the wires 10. It will also be noted that the rear portion of the stem 8 is

reduced and exteriorly threaded for the reception of a nut 12 which is provided with an annular extension 13 in which are spaced notches 14, said notches 14 being to seat a cotter pin 15 which extends through the stem 8 and serves to lock the nut 12 to the said stem, after the manner best shown in Figure 2.

It will be appreciated from the foregoing that my improvement is compact, simple and inexpensive, and that all of the parts that enter into the connection are rigidly fastened to the reflector. Moreover it will be noted that my improvement is susceptible of being easily fabricated or assembled, and that it is devoid of any connections such as are liable to become loose.

It will be appreciated from the foregoing that the slots formed in the annulus 3 are sufficiently deep to permit of the lamp being placed in or adjusted to proper focus.

I have entered into a detailed description of the present and preferred embodiment of my invention in order to impart an exact understanding of the said embodiment in all of its details. I do not desire, however, to be understood as limiting myself to the precise structure and arrangement disclosed, my invention being defined by my appended claims within the scope of which modifications may be made without departure from my invention.

Having described my invention, what I claim and desire to secure by Letters-Patent, is:

1. In combination, a reflector having an aperture and an annulus about the aperture and in the reflector and also having a boss about the aperture at the outer side of the reflector, the said annulus being characterized by diametrically opposite slots, a dielectric stem arranged in said aperture of the reflector and having pins disposed in said slots and also having opposite longitudinal grooves for receiving electric conductors and a threaded rear portion, a lamp bulb joined to said stem, a filament in the bulb and having portions extending through the stem, screws for connecting said conductors to the stem and effecting electric connection between the conductors and the filament, a nut mounted on the stem and disposed in rear of the boss on the reflector and having a notched extension, and a cotter pin extending through the stem and seated in notches of the nut extension.

2. In combination, a reflector having an aperture and an annulus about the aperture and in the reflector and also having a boss about the aperture at the outer side of the reflector, the said annulus being characterized by diametrically opposite slots, a dielectric stem arranged in said aperture of the reflector and having pins disposed in said slots and also having opposite longitudinal grooves for receiving electric conductors and a threaded rear portion, a lamp bulb joined to said stem, a filament in the bulb and having portions extending through the stem, means for connecting said conductors to the stem and effecting electric connection between the conductors and the filaments, and a nut mounted on the stem and disposed in rear of the boss on the reflector.

3. In combination, a reflector having an aperture and an annulus about the aperture

and in the reflector and also having a boss about the aperture at the outer side of the reflector, a dielectric stem arranged in said aperture of the reflector, means between the annulus and the dielectric stem to prevent 25 the rotation of the dielectric stem in the annulus, said dielectric stem having opposed longitudinal grooves for receiving electric conductors and a threaded rear portion, a lamp bulb joined to said stem, a filament in 30 the bulb having portions extending through the stem, means for connecting said conductors to the stem and effecting electric connection between the conductors and the filaments, and a nut mounted on the stem 35 and disposed in rear of the boss on the reflector.

In testimony whereof I affix my signature.

JOSEPH HAROLD SULLIVAN.
